UNITED STATES PATENT OFFICE.

FRANCISCO CONCHA, OF CUZCO, PERU.

COAT-COLLAR HOLDER.

1,328,945.

Specification of Letters Patent. Patented Jan. 27, 1920.

Application filed December 2, 1918. Serial No. 265,039.

To all whom it may concern:

Be it known that I, FRANCISCO CONCHA, a citizen of the Republic of Peru, residing at Cuzco, Peru, have invented certain new 5 and useful Improvements in Coat-Collar Holders, of which the following is a specification.

This invention relates to coat collar holders, having for its primary object to 10 provide a device of simple and improved construction, capable of being readily applied to the clothes of the user, for preventing the coat collar "riding up" into engagement with the neck or hair of the wearer 15 when the latter is in certain positions.

A further object of the invention is to provide a holding device of the character 20 stated, which is readily applied to the garment and which insures proper fitting of the 25 coat collar to the neck of the wearer at all times.

A still further object of the invention is to provide a coat-collar holder capable of being manufactured at low cost, which may be 25 quickly and easily applied to or removed 30 from the garments, which will not interfere with the putting on or taking off of the coat, and which may be easily and quickly 35 rendered operative after the coat has been applied to the body of the wearer.

With these objects in view, together with others which will appear as the description 40 proceeds, the invention resides in the novel formation, combination and arrangement of 45 parts, all as will be described more fully hereinafter, illustrated in the drawings, and particularly pointed out in the claims.

In the drawings:—

Figure 1 is a perspective view of a stud 40 or button constituting a part of the invention,

Fig. 2 is a top plan view of the button,

Fig. 3 is a side elevation of the button,

Fig. 4 is a perspective view of the holding 45 device to be applied to the coat,

Fig. 5 is a face view of the improved holding device, and

Fig. 6 is a longitudinal sectional view 50 taken through the holding device.

The stud indicated generally at 7 in Figs. 1 to 3 inclusive is designed for use in lieu of the collar buttons now generally employed at the back of the shirt or neck band for securing the standing collar thereto. This 55 button or stud comprises a base 8, having a standard 9 projecting at right angles and

centrally therefrom, and a head 10 is secured to the outer end of the said standard. This head is provided with an elongated shank indicated at 11. It will be understood that 60 the improved button is applied to the shirt band in the usual manner and that the shank 11 and head 10 are passed through the button hole in the standing collar. The shank 11 extends downwardly when the device is 65 properly applied to the shirt.

The holder for use upon the coat of the wearer is illustrated in Figs. 4 to 6 inclusive, and comprises an elongated bar 12 having openings 13 therein at its ends to receive stitches whereby the holder is held firmly upon the coat. This holder is to be arranged upon the interior of the coat near the collar thereof and substantially parallel with the shoulders. The bar 12 has arranged 70 thereon a pair of housings 14 arranged in spaced relation and within each of which is pivoted as at 15 the retaining fingers 16. Each retaining finger has a right-angularly disposed arm portion 17, against which bears 80 an expansion spring 18 confined by the housing. Stops 19 are arranged upon the bar to limit the outward swinging movement of the arm portions 17 and the stops are so disposed that when the arms are engaged 85 therewith, the fingers 16 will bridge the space between the adjacent ends of the housings 14.

In practice, the device illustrated in Figs. 1 to 3 inclusive is applied to the shirt band 90 and standing collar in the manner mentioned. The holder shown in Figs. 4 to 6 inclusive is applied to the interior of the coat collar in such position that the shank 11 will be received between the fingers 16 and 95 the bar 12. The said holder may be so positioned as to permit of slight upward movement of the collar before the fingers 16 engage with the standard 9 of the button, or before the head 10 of the button is reached 100 by the said holder. When the coat has moved upwardly until the holder has reached such position, further upward movement of the coat will be prevented, and the collar of the coat will thus be prevented 105 from contacting with the neck or hair of the user. In putting on the coat, the neck portion thereof may be pressed inwardly until the fingers 16 engage the shank 11, whereupon the said fingers will snap over 110 the said shank and will be held thereby. When it is desired to remove the coat, the

collar portion thereof is moved downwardly until the shank 11 becomes disengaged from between the said fingers.

From the foregoing it is obvious that I

5 have provided a holder for coat collars which is of extremely simple construction, and by the use of which soiled and oily coat collars are obviated. The use of such a device also minimizes the rubbing of the coat
10 collar against the linen collar of the wearer thus preventing the linen collar becoming readily soiled.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the appended claims.

Attention is also called to the fact that the wearer can take off the coat regardless of the device constituting the invention since said device will disengage itself.

Having thus fully described my invention, what I claim as new and desire to secure by Letters Patent is:—

1. In a garment holder, the combination 30 with a stud having a pendant shank; of a holder comprising a bar having means for attachment to the inside of the coat, fingers pivotally connected with and outstanding from said bar, and yielding means holding them normally end to end to retain said shank but permitting them to swing inward toward the bar.

2. In a garment holder, the combination 40 with a stud having a pendant shank; of a holder having a bar for attachment to the inside of a coat, a pair of housings outstanding from the inner face of said bar, a pair of L-shaped elements pivoted at their angles to said housings, and yielding means bear-

ing their arms normally toward each other to 45 hold their fingers point to point for admitting the entrance but preventing the exit of said shank.

3. In a garment holder, the combination with a stud having a pendant shank; of a 50 holder having a bar for attachment to the inside of a coat, a pair of housings outstanding from the inner face of said bar, a pair of L-shaped elements pivoted at their angles to said housings, springs within the housing 55 behind the arms of said fingers, and stops on the bar forward of said arms positioned to hold the fingers point to point to permit the entrance but prevent the exit of said shank.

4. A garment holder, in combination, a button including a shank, a holding bar, fingers pivoted in spaced relation upon said bar and extending toward each other, the free ends of said fingers being normally engaged with each other and adapted to confine said shank, arm portions on said fingers, stops limiting the movement of said arms in one direction, and springs normally holding said arms against said stops.

5. A garment holder, in combination, a button including a shank, a holding bar, a pair of housings arranged in spaced relation upon said bar, fingers pivoted in said housings and designed to meet at their free ends 75 in spaced relation from said bar, arms disposed at right angles to said fingers and connected therewith, springs within said housings normally forcing said arms outwardly, and stops limiting the outward movement of 80 said arms.

In testimony whereof I affix my signature in presence of two witnesses.

FRANCISCO CONCHA.
